DESIGN FOR AN ASHTRAY

Paul E. Bennett and George R. Graff,
Toledo, Ohio

Application December 21, 1938, Serial No. 81,917

Term of patent 7 years

To all whom it may concern:

Be it known that we, Paul E. Bennett and George R. Graff, citizens of the United States and residents of Toledo, in the county of Lucas and State of Ohio, have invented a new, original, and ornamental Design for an Ashtray, of which the following is a specification, reference being had to the accompanying drawing, forming a part thereof.

Fig. 1 is a top plan view of an ashtray showing our new design; Fig. 2 is a side elevation thereof; Fig. 3 is a section on line 3—3 of Fig. 1, and Fig. 4 is a section on line 4—4 of Fig. 1.

The dominant feature of the design resides in an ashtray having a cover, the configuration of the cover portion comprising the upwardly and inwardly curved side walls and the transversely extending cigarette supporting portion in which spaced depressions are disposed, as shown.

We claim:

The ornamental design for an ashtray, substantially as shown and described.

GEORGE R. GRAFF.
PAUL E. BENNETT.
